UNITED STATES PATENT OFFICE.

EDWARD S. RAFF, OF CANTON, OHIO.

MUCILAGE-STAND.

SPECIFICATION forming part of Letters Patent No. 653,695, dated July 17, 1900.

Application filed April 9, 1900. Serial No. 12,156. (No model.)

To all whom it may concern:

Be it known that I, EDWARD S. RAFF, a resident of Canton, Stark county, and State of Ohio, have invented certain new and useful 5 Improvements in Mucilage-Stands; and I do hereby declare the following to be a full, clear, and exact description of the invention, such as will enable others skilled in the art to which it pertains to make and use the same.

10 My invention relates to improvements in mucilage-stands.

One object of this invention is to provide a stand of the character indicated that is readily cleaned and replenished and that is simple and durable in construction.

15 Another object of the invention is to provide a mucilage-stand wherein the liability of the mucilage to solidify or harden is reduced to a minimum.

20 With these objects in view and to the end of realizing other advantages hereinafter appearing the invention consists in certain features of construction and combinations of parts hereinafter described, and pointed out 25 in the claims.

In the accompanying drawings, Figure I is a perspective view of a mucilage-stand embodying my invention and shows the movable cover of the stand in its open position. Fig. 30 II is a perspective view of the hood-bearing base of the stand. Fig. III is a perspective view of the mucilage-receptacle of the stand. Fig. IV is a side elevation, in vertical section, on line IV IV, Fig. I, looking in the direction 35 of the arrow, except that in Fig. IV the movable cover of the stand is shown in its closed position.

Referring to the drawings, *a* designates the base of my improved mucilage-stand. The 40 rear portion of the base *a* is provided with a hood *b*, that surrounds the rear portion of the mucilage-receptacle *c*, that rests upon the base. The base *a* extends along the bottom of the inner surfaces of the sides of the hood *b* and extends forwardly of the said sides. The 45 hood-bearing base is composed, preferably, of a metallic casting. The mucilage-receptacle *c* is made, preferably, of glass. The receptacle *c* is provided upon each side and 50 externally, centrally between the forward and rear ends of the receptacle, with a vertically-arranged shoulder *c'*, that extends from top

to bottom of the receptacle and faces rearwardly.

The arrangement of the parts is such that 55 when the receptacle *c* is in position upon the base *a* the rear end of the receptacle will abut against the inner surface of the rear wall of the hood *b* and the shoulders *c*' and *c'* will abut against the forward edge of the different side walls, respectively, of the said hood, and the rear portion of the receptacle occupies the space between the said side walls of the hood and is prevented from lateral displacement by the said walls, and the base *a* 60 is provided, preferably, with a rim or flange *a'*, that surrounds the forward portion of the receptacle *c*.

The hood *b* is formed, preferably, integral with the base *a* and extends over and a suitable distance above and forms a cover *b'* for the rear portion of the receptacle *c*.

70 The cover-forming upper portion *b'* of the hood *b* completely covers the rear portion of the receptacle *c* and is open only between the forward edges of opposite sides of the hood to accommodate access to the rear portion of the receptacle.

75 A movable cover *e* for covering the forward portion of the receptacle *c*, and thereby preventing the exposure of the mucilage within the said receptacle to the external atmosphere when the stand is not in use, is provided, and consists, preferably, of a single piece that is adapted to be moved over and thereby embrace the upper portion of the hood *b* preparatory to taking mucilage from the receptacle *c*, and rests upon and completely covers the forward portion of the said receptacle when the stand is not in use. The stand illustrated has its cover *e* pivoted horizontally and transversely of the stand, as at *e'*, to opposite side walls of the cover-forming portion *b'* of the hood *b*, and the top or central member of the said portion *b'* of the said hood is 80 arranged concentrically of the axis of the cover. The axes of the cover are coincident, and the cover is consequently of the revolving variety, and is enough larger radially than the cover-forming portion of the hood to render it capable of embracing the said portion of the hood in its open position, as shown in 85 Figs. I and II. The cover *e* in its closed position rests upon the forward portion of the 90

receptacle c , forward of the shoulders c' of the said receptacle. The revolving cover in its open position rests upon the shoulder b^2 , formed upon the rear portion and externally 5 of the hood rearward of the bottom of the cover-forming portion of the hood, and rests upon horizontally-arranged shoulders b^3 , that are formed upon and externally of the side walls of the hood. The shoulders b^3 are preferably flush with the upper surface of the forward portion of the receptacle c .

The chamber c^2 of the receptacle c is divided by a partition f , that consists, preferably, of a slide that extends transversely of 15 the said chamber, and is arranged between and in line with the shoulders c' and c . The slide f has opposite ends engaging slideway-forming grooves or channels c^3 , formed in and extending up and down opposite side walls, 20 respectively, of the chamber c' . The portion of the chamber c^2 at the rear of the slide f is designed to hold the larger body of mucilage within the receptacle; but the slide f at its lower edge is cut away at intervals longitudinally of the said slide to form openings or passage-ways f' , that establish communication between the rear portion of the receptacle's chamber at the rear of the slide and the forward portion of the chamber forward 25 of the slide. The slide f at its right-hand end is enlarged upwardly, as at f^2 , and the said upwardly-enlarged portion f^2 of the slide has its upper end forming a brush-rack that is formed by a recess f^3 , provided in the upper edge of the said portion f^2 of the slide, and having its bottom forming a rest for the shank or handle of the brush h (shown in dotted lines) and employed in taking mucilage from the receptacle. The rear wall of the chamber c^2 , rearward of the brush-forming rack 30 of the slide f , is provided with an alcove c^4 to make room for the brush and to confine the brush within the brush-receiving side of the chamber. The rear wall of the chamber c^2 at the left-hand side of the brush-receiving 45 portion of the said chamber has its top c^5 preferably sloping downwardly and forwardly, so that any mucilage lodging thereon will run forwardly into the chamber. The top c^6 of the forward wall of the chamber c^2 , forward of the slide f , slopes rearwardly and downwardly to provide a surface upon which the brush upon taking mucilage from the receptacle can be wiped of its surplus of mucilage 50 and to accommodate the running of any mucilage deposited thereon from the brush or otherwise into the chamber c^2 .

The upper edge of the slide f forms, of course, the principal wiper for removing a surplus of mucilage from the brush.

What I claim is—

1. A mucilage-stand provided with a suitably-supported upright upwardly-removable partition arranged transversely of the chamber between the forward and rear walls of the chamber, which partition is cut away at its lower edge so as to establish open relation be-

tween the forward and rear portions of the chamber, and a brush-rack formed upon the upper edge of the said partition, substantially 70 as and for the purpose set forth.

2. A mucilage-stand having the following: a mucilage-receiving chamber having two upright slideways formed in the opposite side walls, respectively, of the said chamber between the forward and rear walls of the chamber, a sliding partition engaging the said slideways and removable upwardly from the said chamber, which partition has its lower end cut away as required to establish open relation between the forward and rear portions 80 of the chamber, and a brush-rack formed upon the said partition.

3. A mucilage-stand having the following: a mucilage-receiving chamber, a suitably-supported upright partition arranged transversely of the chamber between the forward and rear walls of the chamber and having its lower portion cut away as required to establish open relation between the forward and 90 rear portions of the chamber, a brush-rack formed upon the said partition, and the rear wall of the aforesaid chamber, directly rearward of the rack-forming portion of the partition, being provided with an alcove, substantially as and for the purpose set forth.

4. A mucilage-stand having the following: a mucilage-receiving chamber having the top of its forward wall sloping downwardly and rearwardly to the said chamber; two upright 100 slideways formed in the opposite side walls, respectively, of the said chamber between the forward and rear walls of the chamber, a sliding partition engaging the said slideways and removable upwardly from the said chamber, which partition has its lower portion cut away, as required, to establish open relation between the forward and rear portions of the chamber, and a brush-rack formed upon one end of the said partition.

5. A mucilage-stand having the following: a mucilage-receiving chamber, an upright removable partition arranged transversely of the chamber between the forward and rear walls of the chamber and having its lower 115 portion cut away as required to establish open relation between the forward and rear portions of the chamber, a brush-rack formed upon one end of the said partition, and the rear wall of the aforesaid chamber, directly 120 rearward of the rack-forming portion of the partition, being provided with an alcove c^4 , substantially as and for the purpose set forth.

6. A mucilage-stand having the following: a mucilage-receiving chamber having the top 125 of its forward wall sloping downwardly and rearwardly to the said chamber; two upright slideways formed in the opposite side walls, respectively, of the said chamber between the forward and rear walls of the chamber; a sliding partition engaging the said slideways and removable upwardly from the said chamber, which partition has its lower portion cut away 130 as required to establish open relation between

the forward and rear portions of the chamber; a brush-rack formed upon one end of the said partition, and an alcove formed in the rear wall of the chamber rearward of the 5 rack-forming portion of the aforesaid partition, substantially as and for the purpose set forth.

7. A mucilage-stand having a base, a mucilage-receiving receptacle removably mounted upon the base, a hood rigid with the base and arranged to cover the rear portion of the receptacle and a movable cover for covering or closing the portion of the receptacle that is not covered by the stationary hood.

15 8. A mucilage-stand comprising a base, a mucilage - receiving receptacle removably mounted upon the base, a hood rigid with the base and extending above and over and around the rear portion of the receptacle, and 20 covering the said portion of the receptacle, and a movable cover for covering the remaining portion of the said receptacle.

9. A mucilage-stand comprising a base, a mucilage - receiving receptacle removably mounted upon the base, a hood surrounding the rear portion of and extending above and over and covering the rear portion of the receptacle at the sides and rear, a removable cover for covering or closing the remaining 25 portion of the receptacle, at the sides and front, which last-mentioned cover is supported in such a manner from the stationary hood as to render it, the removable cover, capable of being turned over the stationary hood, or 30 over the receptacle's portion not covered by the stationary hood, according as the movable cover is actuated in the one or the other of its two positions, and shoulders formed upon the stationary hood and arranged to support 35 the movable cover in the latter's open position.

10. A mucilage-stand comprising a base, a receptacle removably mounted upon the base, a stationary hood extending above and over the rear portion of the receptacle and covering the receptacle at the rear and sides, and a movable cover pivoted horizontally and transversely of the stand to the sides of the stationary hood at or near the top of the receptacle, and the relative configuration of 45 the two hoods being such, that the movable cover is capable of being swung over the stationary hood, and is swung over the stationary hood or closed down over the forward portion of the receptacle according as the said movable cover is swung in the one direction or 50 the other.

11. A mucilage-stand comprising a base, a mucilage-receiving receptacle upon the base, a stationary hood extending above and over 60 the rear portion of the receptacle and covering the receptacle at the sides and rear, a movable cover for covering or closing the remaining or forward portion of the receptacle, which last-mentioned cover is supported in 65 such a manner from the stationary hood as to render it, the movable cover, capable of being actuated over the stationary hood, or over the receptacle's portion not covered by the stationary hood, according as the movable 70 cover is moved in the one or the other direction, and two shoulders formed upon and extending up and down opposite sides, respectively, of the receptacle and overlapping the forward edges of the sides of the stationary 75 hood.

Signed by me at Canton, Ohio, this 3d day of April, 1900.

EDWARD S. RAFF.
